ASPIRATOR ASSEMBLY

Russell A. Gulick, Winthrop, Mass., assignor, by
mesne assignments, to Stator Corporation, a
corporation of Rhode Island.

Application December 1, 1937, Serial No. 177,489

6 Claims. (Cl. 230—95)

This invention relates to an improved aspirator arrangement, and more particularly to such an arrangement for use with a relatively heavy propellant fluid such as mercury as, for example, in refrigerating systems employing mercury as a propellant.

In various aspirator installations, it is often desirable to arrange the outlet of the aspirator so that the outflowing fluid is diverted into a duct extending more or less at right angles to the outlet. For example, in a refrigerating system employing mercury as a propellant and employing an aqueous refrigerant, the aspirator may be provided with a funnel having a downward inclination from the propellant nozzle, and the outlet end of the funnel may be connected to an upwardly extending pipe. Since the funnel has a substantial length and since it is desirable to make such systems relatively compact, the funnel may be connected to such a pipe at a point fairly near the throat of the funnel.

Under such conditions I have found, particularly when a propellant such as mercury is employed, that the vapor particles may tend to wear away the wall of the pipe at the end of the aspirator funnel. Apparently, under certain conditions particles of mercury which did not coalesce and condense in the funnel may have sufficient velocity to afford a slight abrading effect. Accordingly the wall of the pipe may become seriously weakened. The present invention affords a simple arrangement to eliminate this disadvantage and to permit the compact installation of an aspirator with a vapor receiving duct extending at a relatively sharp angle to the outlet of the aspirator funnel.

To permit this desirable result, I preferably dispose material in the path of the particles at the juncture of the outlet and receiving pipe, which material is substantially immune to deterioration under the action of high velocity particles.

Further features of the invention relate to the arrangement of parts so that an adequate surface of liquid mercury can be provided to afford the desired protective results without requiring the use of an unduly large quantity of mercury and to permit the satisfactory structural arrangement of the parts of the system to maintain the mercury pool at the desired point.

In the accompanying drawing:

Fig. 1 is a diagrammatic view of an improved refrigerating system including an improved

aspirator assembly constructed in accordance with this invention; and

Fig. 2 is an elevational view of an aspirator assembly, with parts shown in section.

5. My invention may be used in general in combination with aspirators, and particularly with such aspirators employing relatively heavy propellants such as mercury, but the invention is more particularly applicable to a refrigerating system which should be relatively compact, such a system being diagrammatically disclosed in Fig. 1 and being of the general type disclosed in United States Patent No. 1,761,551 to Eastman A. Weaver.
15. The system shown in Fig. 1 comprises a boiler 1 provided with a heating element, such as an electrical heater 2, and connected to the lower end of a riser pipe 3. Mercury vapor from the boiler 1 flows upwardly through the pipe 3 and passes through a nozzle 4 forming a portion of the aspirator assembly. This assembly also includes a mixing chamber 6 which is connected by a vapor duct 7 to an evaporator 8 containing a body of liquid refrigerant such as aqueous solution. Mercury vapor issues from the nozzle 4 at high velocity and draws refrigerant vapor from the evaporator 8 through the duct 7. The mixed vapors flow into a funnel 9 which preferably is inclined and which is provided with 25. cooling means such as fins 10. Mercury which has condensed in the funnel 9 passes from the outlet of the funnel into the longer leg of a trap 12 and the pumped vapor flows upwardly 30. through a fluid-receiving pipe 16 to a condenser 17. The lower end of the latter is connected to a refrigerant return duct 18 which provides a trap 19 containing a body of the heavy propellant.

35. As liquid refrigerant piles up in the pipe 18, a sufficient head is provided in that leg of the trap to permit the refrigerant to bubble through the mercury and to return to the cooler 8. A trap is connected to the bottom of the evaporator 8 to receive stray propellant therefrom and 40. is connected by a pipe 22 to a mercury return pipe 23; the latter contains a column of mercury to balance the boiler pressure. The trap 12 is also connected to the pipe 22 while the upper end of the pipe 23 is provided with a continuation 45. 23a to receive condensed mercury from the mixing chamber 4.

50. Since the funnel 9 is preferably inclined at a moderate angle to the horizontal, e. g., at an angle of the order of 15 degrees, and since the aspirator assembly may be relatively long, it may

be desirable to have the receiving pipe 16 extend at an acute angle from its juncture with the outlet, as shown in Fig. 1.

In accordance with this invention, means is provided at the junction of the funnel and the receiving pipe to prevent the fluid emitted from the funnel from undesirably abrading the metal wall of the system, as otherwise might occur were such means not provided.

Fig. 2 illustrates a funnel of the general character shown in Fig. 1, similar parts being identified by similar reference numerals, but this figure shows in more detail the preferred arrangement of such a funnel. The aspirator assembly shown herein may include a funnel having a bore with inwardly tapered portions 28 and 29 and a throat 30, the funnel also having a flared outlet portion 31. A funnel of this general form is more fully disclosed in the copending application of Lyman F. Whitney, Serial No. 177,749, filed December 2, 1937. The pipe 16 extends at an acute angle to the outlet portion 31, the latter being downwardly inclined and the adjoining receiving pipe section being substantially vertical.

In accordance with this invention, a small chamber 35 may be provided at the side of the pipe 16 opposite the end of the funnel. This chamber may be in the form of a short tubular section and may be provided with a tapered portion 37 which decreases in diameter as it extends away from the pipe 16 and which terminates in a closed end 38. Thus the member 35 provides a tubular pocket which inclines downwardly from the juncture of the funnel outlet and the receiving pipe 16. This pocket may contain a body 40 of liquid mercury, the surface of this mercury obviously being horizontal and lying in such a position that particles of mercury which issue from the outlet of the nozzle at high velocity may impinge on the surface at an acute angle thereto, e. g., an angle of 15 degrees, thus having their kinetic energy absorbed. When the particles coming directly from the funnel pass into the liquid, their direction of movement is such that they may follow a relatively long path in the liquid, although the pool is quite shallow.

Particles which are following paths above the surface of the mercury pool may strike the upper portion of the tapered section 37 and may thus be deflected so that they also strike the pool. Thus an arrangement is provided to avoid the direct movement of mercury particles into contact with a surface at right angles to the path of vapor flow.

Fig. 2 also shows a preferred structural arrangement of the parts at the end of the aspirator assembly, the tubular section 35 having a diameter which permits it to fit over the outlet end 31 of the funnel so that these parts may be welded together. The pipe 16 is provided with two circular openings communicating respectively with the funnel and with the short tubular section 35. The pipe 16 extends through openings in the section 35 and these parts are welded to each other. The lower end of the pipe 16 has a tapered portion fitting within the flared end of the long leg of trap 12.

It is evident that vapor particles issuing from the funnel 9 at low speed may readily turn with the rest of the vapor stream and flow upwardly through pipe 16, but that particles which are still moving at high speed move across the lower end of pipe 16 and eventually find their way

into the pool 40, either directly impinging on the surface of this pool or striking the inclined upper surface of the tapered portion 37 and being deflected into the pool. In either case, the energy of the particles is absorbed to a substantial degree by the liquid mercury. Since this liquid mercury does not wear out, such an arrangement affords a junction between the ducts of the system which is capable of lasting for an indefinitely long period.

Should mercury be lost from the pocket 35 for any reason, the mercury pool is automatically replenished by mercury particles which issue from the funnel and pass into the pocket. On the other hand, the juncture between the pocket 35 and the pipe 16 affords a spill-over so that excess mercury from the pool drains into the trap 12 and thence passes to the return pipe 23. Thus an arrangement is provided automatically to assure the maintenance of the mercury pool at the desired level to absorb the shock of high velocity particles, while permitting a relatively small amount of mercury to be employed for this purpose.

It should be understood that the present disclosure is for the purpose of illustration only and that this invention includes all modifications and equivalents which fall within the scope of the appended claims.

I claim:

1. Aspirator assembly of the class described comprising a nozzle, a compression funnel having a downwardly extending outlet portion, a pipe extending at an angle to said portion to receive vapor therefrom, and a short tube terminating in a closed end, said tube being aligned with the outlet portion of the funnel, said tube having an inwardly tapered wall and forming a liquid-containing pocket, whereby particles leaving the outlet at high velocity either directly impinge on the liquid or are deflected by the wall to pass into the liquid.

2. Aspirator assembly of the class described comprising a nozzle, a compression funnel having a downwardly inclined outlet portion, a pipe extending at an angle to said portion to receive vapor therefrom, and a chamber disposed at the opposite side of the pipe from the outlet portion, said chamber having an inlet aligned with the outlet portion of the funnel and affording a shallow liquid-containing pocket, thereby to support a pool of liquid so that vapor particles which leave the outlet at high speed may strike the surface of the liquid at an angle thereto, and a drain having a spill-over connection with the tube to limit the level of the pocketed liquid.

3. Method of absorbing the energy of high velocity fluid particles at the outlet of an aspirator which comprises directing some of the particles along substantially straight paths against the surface of a body of liquid and deflecting other particles against said surfaces by a surface at an acute angle to the surface of liquid.

4. Aspirator assembly of the class described comprising a compression funnel, a mixing chamber at the inlet of the funnel, a nozzle extending into the chamber to deliver mercury to the same, said funnel being provided with a throat spaced from the nozzle, cooling means for the funnel, said funnel having an outlet portion, a vapor-receiving pipe connected to said outlet portion and extending at an angle thereto, a short tubular section having openings through which the pipe extends and having an end interfitting with the end of the outlet portion, the wall

of said pipe having opposite openings registering respectively with the outlet portion and the bore of the tubular section, the section having a closed end and affording means to absorb the shock of high velocity particles which do not pass directly from the outlet portion into the pipe.

5. Aspirator assembly of the class described comprising a nozzle, a compression funnel having a relatively straight outlet portion, a receiving pipe extending at an angle to said portion to receive vapor therefrom, and a shock absorbing means opposite said outlet, said means including a chamber containing a body of liquid whose upper surface meets a metal surface at an oblique angle, thereby providing mutually 10 converging metal and liquid surfaces which high 15

velocity particles may strike while moving at acute angles thereto, whereby the kinetic energy of the particles is absorbed.

6. Aspirator assembly of the class described comprising a nozzle, a compression funnel having an outlet portion, a pipe extending at an angle to the outlet of the funnel to receive vapor therefrom, and a tube disposed to receive high velocity particles which do not pass along said pipe from said outlet, said tube affording a liquid-containing pocket, the tube having a wall positioned to deflect high velocity particles to cause them to pass into the liquid, and a drain having a spill-over connection with the tube to limit the level of the liquid in said pocket.

RUSSELL A. GULICK.
